GUN TEST RANGE

Ralph M. Ferguson, Dayton, Ohio

Application February 6, 1945, Serial No. 576,437

4 Claims. (Cl. 273—102.4)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to gun test ranges.

A purpose of the invention is to provide a means for testing machine guns, cannon, accessories and the like by actual firing of the guns.

A further purpose of the invention is to provide a test range which is very short in length.

Another purpose of the invention is to provide a means of stopping the bullets on a short test range with safety to the personnel and equipment employed during the test.

Other purposes of the invention will become apparent from the following description and drawings.

A preferred embodiment of the invention has been illustrated in the drawings in which

Figure 1 is a sectional elevation view of a device embodying the invention.

Figure 2 is an elevational view taken along the line 2—2 on Figure 1.

Figure 3 is a fragmentary transverse section, showing the mounting on the pipe 40.

Figure 4 is a sectional view taken along the line 4—4 of Figure 1.

Figure 5 is a horizontal section on the line 5—5 of Figure 1, but not showing the concrete base, and

Figure 6 is a plan view taken along the line 3—3 of Figure 1.

Test firing of automatic weapons such as machine guns and 20 mm. automatic cannon may be done on a full size range laid out over an area of land or partly over land and partly over water. However, this has the disadvantage of requiring large isolated areas to be reserved solely for use in range firing, for reasons of safety.

The present invention provides a range for test firing of this type of weapon, the range being housed in a relatively small structure. The invention has the advantage of being safe to use, and of providing means for salvaging the metal in fired bullets.

As seen in the drawings, particularly Figure 1, the range includes a gun chamber 1 and a target chamber 2.

An automatic weapon 3, such as a machine gun or a 20 mm. automatic cannon, or the like, is mounted on a pedestal or support 4 having a flat top 5 and four legs 6.

A partition wall 7, having a heavy steel front portion 8 and a fire-proof and soundproof back portion 9, within chamber 2 separates the gun

chamber 1 from the target chamber 2. The wall 7 has a horizontal opening 10 formed through it at the height of the gun barrel 11 of the weapon 3.

In the target chamber 2, there is a massive steel target block or bullet deflecting and energy dissipating member 12, rectangular in cross-section against the flat face 13 of which the bullets fired from the weapon 3 impinge. The block 12 is made of battleship armor and its dimensions may be approximately 24 inches wide, 24 inches square, and 16 inches thick. Its face 13 makes an angle of about 75 degrees with the horizontal line of fire and about 15 degrees with the vertical as indicated in Figure 1, although the angle of inclination may be greater if desired.

It is desirable to make the block 12 quite thick and strong so the bullets striking against it will not move it or penetrate it. Battleship armor, 16 inches thick, is deemed preferable for this use if available, although other armor plate of comparable characteristics may be used.

A truncated hollow conical member 14, has its smaller end 15 secured to the face 13 of the block 12 by welding or other suitable means, the axis of the member 14 being perpendicular to the face 13. There is a member 17, forming the base of the cone 14, the base angle 16 of the cone being 62 degrees in the preferred embodiment of the invention shown, the truncated cone having an outside diameter of five feet at the base 17, and narrowing down to two feet where it joins the target 12. The base 17 and sides of the cone may be made of armor plate, two inches thick, and any joints are preferably welded. It is seen that the target 12, the frustro-cone 14 and the base 17, form a chamber unit when welded together, and this unit which will be called the cone-target, is mounted on a concrete base 18 as shown.

A backstop 19, formed of bales of pressed steel, is placed behind the target 12, against the wall 20, its base 22 being supported on and surrounded by concrete in the concrete base 18 as indicated.

A transversely arranged vertical baffle 23, having a curved lower surface 24 to conform to the contour of the cone, is secured to the lower inside surface of the cone 14 spaced a short distance rearward from the base 17, as in Figures 1 and 4. The baffle 23 may be made of 2 inch thick armor plate, being 12 inches wide along its upper surface, and about five inches high.

A horizontal steel tube 25 about three feet long, having flanges 26 and 27 fixed at its ends, serves to connect the gun chamber 1 to the interior of the cone-target, the flange 27 being fastened to the base 17 opposite to and overlapping the perim-

entral edges of an opening 28 formed through the base 17. This opening constitutes a bullet-receiving port, the effective clearance in which is defined by the end of the tube 25, which thus confines the path of the entering bullets to approximately two and a half inches.

The opening 28 is made large enough to serve as an inspection hole for looking into the interior of the cone-target by removing the tube and flange 27. The inclined flange 27 which is made of two inch thick armor plate, is removably secured to the cone base 17 by means of bolts 29 which are threaded into holes in the base 17. It will be noted that the hole 28 is located a short distance above the center of the cone base 17, so that the bullets moving approximately on the axis of the tube will impinge approximately on the center of the face 13 of the target plate 12.

The tube 25 is made of steel one and one half inches thick, its inside diameter being two and one-half inches. The tube which is about 3 feet long, is about 40 inches above the floor and its axis is at the same height as the axis of the barrel of the gun being fired and as the center of the face 13 of the target 12. The flange 26 is removably secured to the wall 7 by means of bolts 29. A disk 30 having bolt holes corresponding to those in the flange 29, is fastened over the hole 10 in the wall, the bolts 29 passing through it and nuts threaded over the ends of the bolts thereby securing the disk 30 and the flange 26 to the wall. The disk 30 is provided with a central opening through which the gun barrel 11 protrudes into the tube 25.

Holes 31 in the tube 25 permit gases and dust to escape into chamber 2, the exhaust fans 32 serving to draw the gases into the chamber. Sprinkler heads 33, connected to water pipe 34, are set to operate if the temperature of the inside of chamber 2 should become too high.

An opening 35, about one-eighth of an inch wide by 12 inches long is formed through the upper wall of the cone 14 at its narrowest portion by cutting or grinding away part of the cone where it touches the face 13 of the target 12. A housing 36, made of steel side walls 37 and top member 38, covers the opening 35 and forms a chamber 39 over it. A pipe 40, connected to the chamber 39 through a hole 41 in the top member 38, leads at its other end, (not shown), to a water supply. By causing water to flow in the pipe 40, a sheet of water will flow through the opening 35 into the interior of the cone 14 and across the face of the block 12, serving among other purposes, to cool the surface of the target face 13 and other interior surfaces, and to flush away debris.

To allow water and debris to leave the cone, an outlet opening 42 is formed through the wall of the cone 14, and the opening leads to a clean-out chamber or waste bin 43 through a waste pipe or chute 44 set or formed in the concrete base 18. An inclined ramp 46 allows access to the waste bin 43 for cleaning it out. A door 47 made of steel and arranged for vertical movement in guides 48, serves for opening or closing the bin 43 as desired. A counterweight 49, connected to the door 47 by means of a cable 50 passing over sheaves 51, serves to counterbalance the weight of the door 47 to facilitate its movement. A drain 67 is provided to drain water from the bin.

The outer surfaces of the cone 14 and base 17 are coated with a suitable material to minimize noise and vibration.

A fan 52 is provided in the wall of gun chamber 1 to ventilate the chamber. The external walls, floor and ceiling of the two chambers 1 and 2 are strongly made of concrete, the construction of wall 7 having already been described.

In order to accommodate different size guns 3, the table top is provided with means for elevating and lowering it. As indicated in Figures 1 and 6, there are four vertical brackets 53 bolted to the floor by means of bolts or lug screws 54. Each bracket 53 has a vertical guide portion 55 which is L-shaped, the four guide portions being thus arranged at the four corners of the table top 5 and serving to guide it and prevent horizontal movement of the table top as it moves vertically between the guide portions.

The four legs 6 are each pivotally connected at their upper ends to lugs 56 projecting down from the table top 5, and are each pivotally connected at their lower ends to couplings 57, 58, 59 and 60 which in turn are threaded onto horizontal rods 61 and 62 which pass through holes in the brackets 53 as shown. The threaded portions of rods 61 and 62 engaging couplings 57 and 59 are provided with right hand threads, while the portions of the rods engaging couplings 58 and 60 have left hand threads. Cranks 63 and 64 are attached to rods 61 and 62 as shown, and the rods also have removable stops 65 secured to them to prevent longitudinal movement of the rods. It is thus apparent that turning the cranks 63 and 64 in one direction elevates the table top by bringing the lower portions of the legs 6 closer together, while turning the cranks in the opposite direction separates the legs and thus lowers the table top.

The table top 5 is provided with upwardly projecting lugs 66 having transverse holes for fastening the gun 3 to the table top. In installing a gun for test firing, the barrel 11 of the gun is first inserted into the central opening in the disk 30 so it projects into the tube 25, and then the gun is secured to the top 5 of the table. It is then ready for firing.

The particular arrangement of the frusto conical hollow cone 14, has peculiar advantages in avoiding too great an angle of incidence of deflected bullets and flying particles on impact with these walls, reducing velocities so that when such bodies encounter the front wall 17 a minimum of erosion occurs, permitting the relatively thin walls of the cone and the base wall 17 to attain a life commensurate with that of the block 12.

It will be seen that replacement of the block 12 and cone 14, and base 17 may be effected by simply lifting the unit from the concrete base and setting a new one in place, the pipe 40 and box 36 being disconnected and reconnected in any approved order and the connections at the tube 25 being designed in accord with approved practices.

The quality of baled steel is well understood, and it affords a novel resilient shock absorber by which the excess of force in the impact of the bullet not balanced by the inertia of the block 12 is absorbed with an almost imperceptible degree of movement of the cone target.

Although I have described the invention in specific terms it is to be understood that numerous changes may be made in the size, shape, arrangement and materials without departing from the spirit and scope of the invention as claimed herein.

I claim:

1. In a testing range for testing rate of fire

and serviceability of gun actions, a gun support to hold a gun in a desired firing position, a bullet-proof bullet-receiving chamber having a bullet-receiving port in its front side approximately concentric with the axis of the bore of a gun in the support, a bullet deflecting body having a mass greatly in excess of that of the bullet so that a large part of the kinetic energy of the moving bullet may be readily absorbed by the bullet deflecting body, said mass being effective at a central point of impact on the body, said body having a forward face inclined to the said axis, said chamber having side walls united with said deflecting body and divergent forwardly, said chamber having also an eccentrically ported forward wall united with the side walls to form a closed chamber, a line central in said chamber normal to said face of the deflecting body being approximately coincident with said bore axis at said surface, said chamber having an effluent port for collected bullets, and means to cool the face of the deflecting body.

2. The structure of claim 1 in which means is included to project a sheet of water against and across the said face of the deflector body.

3. The structure of claim 1 in which a guiding tube is fixed concentric with said axis, receiving the muzzle portion of a gun on said support, and extending to and joining said chamber coincident with said bullet receiving port, means being included to vent gun source gases.

4. As an improved article of manufacture a bullet collector for bullets fired from a weapon, comprising a chamber having a hollow frusto-conical body wall, a deflector body united with

the smaller end of the said wall and having a forward face normal to the conical axis of the chamber and including the entire cross-sectional area of the small end of the frustum, said body having a mass greatly in excess of that of the bullet so that a large part of the kinetic energy of the moving bullet may be readily absorbed by the bullet deflecting body, said chamber having a forward wall united with its base throughout the circumference of the latter, a discharge port being formed adjacent the junction of the conical wall and said front wall at one side of the chamber, said front wall having a bullet receiving port therein spaced from the conical axis of the chamber opposite the discharge port, and a bullet guiding tube fixed with the front wall surrounding said bullet receiving port and extending on a line with the incidence of said conical axis and said forward face of the said deflector body.
